INVENTOR:

Rudolf Loeb,
by Murray G. Boyce Atty.

UNITED STATES PATENT OFFICE.

RUDOLF LOEB, OF VENTNOR, NEW JERSEY.

ORNAMENTAL FABRIC STRUCTURE.

Application filed March 1, 1927. Serial No. 171,855.

My invention relates to ornamental fabric structures, more particularly those such as curtains or similar draperies which are provided with edged portions of an ornamental character produced by arranging 5 separate sections of material with reference to each other to produce an artistic or ornamental effect, and one object of my invention is to provide an edging strip or ruffle material made of two sections of fabric, one 10 of which is narrower than the other; said sections being secured together in superposed position and in such relation with respect to each other that the edge, which 15 may be a folded edge, of one of the sections projects beyond the edge, which may be a folded edge, of the other section and gives the effect of "piping", and at the same time serves as a "facing" for the outer section 20 when applied as a ruffle to a section of fabric which may be employed as a curtain, or for other purposes.

A further object of my invention is to arrange these sections of fabric so as to produce an ornamental edge effect by combining 25 independent sections or strips of material of different character and/or color which are sewn together by a line of stitches directly adjacent to the edges, which may be 30 folded edges, of said fabric sections in the formation of an edging or ruffle strip to be subsequently applied to the margin of the material to be ornamented, whereby one 35 of said independent strips or sections of material occupies such position with respect to the other independent strip of material that the edge, which may be a turned or folded edge, of said narrow strip projects beyond the edge, which may be a turned or folded 40 edge, of the other strip; producing an effect of "piping".

In the preferred arrangement this duplex strip of material, wherein one edge of each piece may be turned or folded over and the 45 said edges, which may be the folded edges with their inturned portions adjacent each other are secured together by a line of stitches directly adjacent to said edges, which 50 may be the folded edges, with one edge, which may be a folded edge, projecting beyond the other edge, which may be a folded edge, is made as an entity to be subsequently applied to and form the ruffled edge of a curtain structure; the outer margin or raw edge of the flounce portion of 55 the wider strip of material forming such

border or ruffled edge being hemstitched, overstitched, or otherwise prepared to produce a finished effect.

The duplex ruffle strip is secured to the material it is to ornament preferably by a double row of parallel stitches applied at a single operation during the ruffling by suitable mechanically operated sewing mechanism; the raw edge of the curtain or other material receiving the ornamental edging being turned in to enclose and cover the raw edge of the narrower section forming part of the duplex edging strip, and the several plies of material being secured together 70 by such double row of stitches.

My present invention comprehends an edging for a body fabric comprising a ruffle structure consisting of an upper strip of material and a lower strip of material superposed upon each other with an edge of the lower strip projecting beyond the edge of the upper strip to form a piped edge for the upper strip; the two strips being secured to each other by a line of stitching adjacent 80 to the piped edge of the upper strip, and both of the strips being ruffled along the piped edge and secured to the body fabric with the lower strip between the upper strip and the body fabric by a line of stitching 85 spaced inwardly of the piped edge and the first line of stitching.

A further feature of my invention is the utilization of strips of different color, that is to say the lower strip of one color and 90 the upper strip of another color; said strips being applied to the body fabric in the manner just described.

These and other features of my invention are more fully described hereinafter; reference being had to the accompanying drawings, in which:

Figure 1 is a view in elevation of a strip of duplex material employed as the ruffled or other edge in the formation of ornamental fabric structures within the scope of my invention.

Fig. 2 is a sectional elevation taken on the line II-II, Fig. 1.

Fig. 3 is a view in elevation of an ornamental fabric structure, a curtain for instance, partly broken away, in which the strip of duplex material shown in Figs. 1 and 2, is employed as a ruffled edging, and

Fig. 4 is a sectional view on the line IV-IV, Fig. 3, partly in perspective.

In Figs. 1 and 2, I have illustrated a strip

of duplex material subsequently employed as an ornamental ruffle edging for application to a fabric in the preparation of curtain draperies or other similar structures, which 5 comprises a narrow section of material, indicated at A, and a wider section of material, indicated at B. The narrow section A, together with the wide section B, is fed through suitable folding devices constituting 10 sewing machine attachments whereby the edges of both sections of material are turned over and disposed toward each other as indicated at a and b; the turned portion a of the section A being somewhat wider than 15 the turned portion b of the section B, and following the turning operation by the folding guides referred to, the turned edges a and b of the sections A and B, superposed upon each other in the manner indicated by 20 Fig. 2, are presented to a needle for a line of stitching, indicated at 1, directly adjacent to the folded edge of the section B, whereby the two sections are confined together, with the folded edge of the narrow section projecting 25 beyond the folded edge of the broader section to produce the piped effect.

The duplex strip of material so produced is then presented to a ruffling machine which applies the same to an edge of a piece of 30 curtain fabric indicated at C, and the finished product is clearly shown in Fig. 3, wherein the ornamental ruffle composed of the strip of duplex material made up of the sections A and B, presents the effect of 35 "piping" by reason of the folded edge a' of the section A projecting beyond the folded edge b' of the section B. This duplex strip to form the ruffled edge of the curtain or other fabric structure may be secured there- 40 to by two parallel rows of stitches 2, which may be simultaneously applied by any suitable form of two-needle sewing machine, and these stitches 2 confine the raw edge of the section A, and the turned over edge c, 45 of the curtain or other fabric structure C, as clearly indicated in Fig. 4.

The inner portion of the ruffled edging shown in Fig. 3, or that part directly adjacent to the curtain or other fabric structure 50 is duplex; being made up of a portion of the section B and the section A, and the latter, in addition to its folded edge forming a "piping" with respect to the folded edge of said section B, faces the latter and 55 presents a highly ornamental effect in connection with the "piping" when portions of the narrower part of the ruffle turn over and display such facing, as indicated in Figs. 2 and 3. The flounce portion of the 60 ruffle, beyond the stitches 2, is formed wholly of the section B, which may have its raw edge hemstitched or bound by a suitable form of overedging stitch, indicated at 3.

By using material of one color or character 65 for the section A, and similar material,

but of a different color, or material of another character, for the section B, the effect of a piped edge is produced by the lateral displacement of the folded edge a' of the one section with respect to the folded edge 70 b' of the other section, and such "piped" edge produces a highly ornamental effect in connection with the curtains or other articles of fabric with which it may be employed. 75

While my improved ruffle strip has been described as particularly applicable to curtains and draperies of a similar character, it will be understood that its use is not limited to such structures and that it may 80 be used as an ornamental edging for any fabric structure, including pillow and cushion covers, shelf draperies, hangings, and the like, without departing from my invention. 85

As this application contains matter in common with and divisible from my application for patent filed December 15, 1926, under Serial Number 154,904, it is to be considered as a continuation of such prior 90 application in so far as the common subject-matter is concerned.

I claim:

1. An edging for a body fabric comprising a ruffle structure consisting of an upper strip of material and a lower strip of material superposed upon each other with an edge of the lower strip projecting beyond the edge of the upper strip to form a piped edge for the upper strip, the two strips being secured to each other by a line of stitching adjacent to the piped edge of the upper strip and both of the strips being ruffled along the piped edge and secured to the body fabric with the lower strip between the upper strip and the body fabric by a line of stitching spaced inwardly of the piped edge and the first line of stitching. 100

2. An edging for a body fabric comprising a ruffle structure consisting of an upper strip of material and a lower strip of material superposed upon each other with a turned edge of the lower strip projecting beyond a turned edge of the upper strip to form a piped edge for the upper strip, 110 the two strips being secured to each other by a line of stitching adjacent the piped edge of the upper strip and both of the strips being ruffled along the piped edge and secured to the body fabric with the lower strip between the upper strip and the body fabric by a line of stitching spaced inwardly of the piped edge and the first line of stitching. 115

3. An edging for a body fabric comprising a ruffle structure consisting of an upper strip of material of one color and a lower strip of material of another color superposed upon each other with an edge of the lower strip projecting beyond the edge of 125

the upper strip to form a piped edge for the upper strip, the two strips being secured to each other by a line of stitching adjacent the piped edge of the upper strip and both 5 of the strips being ruffled along the piped edge and secured to the body fabric with the lower strip between the upper strip and the body fabric by a line of stitching spaced 10 inwardly of the piped edge and the first line of stitching.

4. An edging for a body fabric comprising a ruffle structure having a free piped edge consisting of an upper strip of material and a lower strip of material superposed upon each other with the lower strip pro-

jecting beyond the upper strip to form a piping for the upper strip and facing or lining the underside of the latter, the two strips being secured to each other by a line of stitching adjacent the free edge of the 20 ruffle structure and both of the strips being ruffled along the free edge of the ruffle structure and secured to the body fabric with the lower strip between the upper strip and the body fabric by a line of stitching spaced 25 inwardly of the piping and the first line of stitching.

In witness whereof I have signed this specification.

RUDOLF LOEB.
